(57) **CLAIM**

We claim the ornamental design for an inflatable dart board, as shown and described.

DESCRIPTION

FIG. 1 is a top rear left perspective view of an inflatable dart board according to the new design;

FIG. 2 is a top front left perspective view of the inflatable dart board shown in FIG. 1;

FIG. 3 is a top plan view of the inflatable dart board shown in FIG. 1;

FIG. 4 is a bottom plan view of the inflatable dart board shown in FIG. 1;

FIG. 5 is a right side elevation view of the inflatable dart board shown in FIG. 1;

FIG. 6 is a left side elevation view of the inflatable dart board shown in FIG. 1;

FIG. 7 is a rear elevation view of the inflatable dart board shown in FIG. 1; and,

FIG. 8 is a front elevation view of the inflatable dart board shown in FIG. 1.
